Attorney Harry L Duncan

UNITED STATES PATENT OFFICE.

GEORGE ALBERT LYON, OF PHILADELPHIA, PENNSYLVANIA.

BUFFER CONSTRUCTION.

Application filed April 21, 1923. Serial No. 633,600.

To all whom it may concern:

Be it known that I, GEORGE ALBERT LYON, a citizen of the United States, and resident of Philadelphia, county of Philadelphia, 5 State of Pennsylvania, have made a certain new and useful Invention Relating to Buffer Constructions, of which the following is a specification, taken in connection with the accompanying drawing, which forms part of 10 the same. This application is a partial continuation of my copending application, Serial No. 632,076, filed April 14, 1923, and contains subject matter taken therefrom.

This invention relates to automobile buffers or bumpers in which one or more of the buffer front elements may advantageously be formed of relatively wide thin strip such as spring steel one and three-quarters to two and a half inches wide and one-quarter to 20 three-eighths of an inch thick more or less, which may be recurved or otherwise formed as by being diagonally folded to form a transversely extending connector portion and integrally connected transversely separated 25 strip members which may be oppositely inclined adjacent the connector portion and extend in the same or opposite directions therefrom. Such a buffer element may be advantageously used at the lateral ends of 30 the buffer adjacent the automobile wheels and in such cases the transverse connector portion may have its diagonal folds arranged at substantially right angles to each other so that two transversely separated strips extend horizontally inward from this 35 connector portion to form a double height or double strip buffer element which may extend inward to or past the center of the buffer, if desired, and be adjustably or otherwise joined in overlapping reenforcing position with similar horizontal strip members which are joined by a transverse diagonally folded connector portion at the other side or end of the buffer. Such a buffer front may 40 be supported in any desired way and a spring steel strip supporting attaching member, may be arranged to be connected to the two frame ends and have forwardly extending connecting portions secured to these buffer 45 front strip members on each side of the center of the buffer front and within a foot or so of the buffer ends so that these transverse connector portions at the buffer ends are not subjected to excessive strains which are 50 largely transferred from each of the front strips directly to the connected buffer sup-

porting member which is considerably wider than the vertical separation between the front strips. In some cases the connector member may be bent round in more or less 60 conical form which, when the recurved end of the element is bent backward considerably out of line with the connected transversely separated strips or members, brings them nearly or entirely into vertical alignment, if 65 desired, throughout the body of the front element, although for a distance adjacent the connector portion they may be oppositely inclined. This conical bent connector portion may of course be flattened in some cases 70 to form a funnel shaped bend at the recurved end of the strip element which gives a more compact construction. In some cases, however, where the recurved end is not bent so far back out of line with the connected 75 front strips, the inclination of the conical bent end need not be so great and this arranges the adjacent oppositely bent strips at a correspondingly greater inclination to each other, so that their adjacent inner portions 80 should be oppositely twisted if they are to be brought nearly or entirely into vertical or transverse alignment with each other. These double strip buffer elements may be readily finished since the substantially parallel or horizontally extending front strip members together with the rear face of the connector portion may be ground, polished and nickel plated, if desired, while the other faces of the strips may be finished in baked 85 enamel or other suitable material of less prominent appearance so that the conically bent or folded edges which are rounded over at the buffer ends give a striking appearance to this type of construction. Generally similar buffer elements having transversely separated strip members connected by integral diagonally folded transverse connector portions may of course be used in other parts 90 of the automobile buffers with advantage and buffer supporting members may be formed in this way and connected in any suitable way to the car frame. Buffer fronts may be made up of one or more separate front strips in addition to two adjustably 100 connected elements having transversely extending end connector portions joined with the transversely separated buffer front strips or, if desired, a single strip may have such transverse connector portions at both ends 105 and may have the strip ends welded or otherwise secured together so as to form, if de-

sired, an overlapping reenforcing portion on the upper or lower front strip adjacent to the buffer center between the clamping connecting devices which may be used to connect these front strips to the cooperating supporting members used. Also, if desired, a unitary double height buffer front may be made up in this way so as to be somewhat shorter than the width of the buffer laterally across the vehicle, and this double strip front member may be connected in any suitable way to a single height strip buffer front of the Lyon type construction, for instance, so as to form a central impact receiving portion of increased vertical width in some cases.

While of course it is sometimes desirable to have the buffer front strips substantially aligned with each other transversely, or vertically at the center of the buffer front and even adjacent the transversely extending bent or folded connector portion integrally joining them, yet for some purposes this folded connection may advantageously be arranged so that the adjacent portions of the strip members are arranged at an angle to each other; thus instead of being vertically or transversely aligned throughout they may be either convexly or concavely curved in cross section or each oppositely inclined and arranged at an angle of ten to twenty degrees more or less from the vertical line parallel to the transverse connector portion so as to form a generally convex or concave arrangement of the strips, which gives them additional stiffness and strength where desired. Such constructions make it possible to form integral rearwardly bent supporting elements by rearwardly bending portions of the oppositely inclined strip members adjacent the two ends of the buffer front from the diagonally opposite upper and lower strips on the ends so as to form rearwardly extending strips which may be clamped to the sides of the car frame members if desired. Also by bending these oppositely inclined front strips straight backward on themselves and then forming in-turned ends thereon at the desired distance back from the buffer front, these inturned ends may be brought and held together in overlapping position so that they may be clamped or otherwise secured to the frame ends or other parts of the automobile frame members.

In the accompanying drawing showing in a somewhat diagrammatic way a number of illustrative embodiments of this invention

Fig. 1 is a front view of a buffer.

Fig. 2 is a top view thereof.

Fig. 3 is an enlarged transverse section taken along the line 3—3 of Fig. 1.

Figs. 4 and 5 are transverse sections through buffer front constructions.

Fig. 6 is a transverse section through another form of buffer taken along the line 6—6 of Fig. 8.

Fig. 7 is a rear view thereof.

Fig. 8 is a top view of the same.

Fig. 9 is a front view of another buffer element.

Fig. 10 is a top view thereof.

Fig. 11 is a front view of still another buffer element, and

Fig. 12 is a top view of the same.

The buffer front shown in Figs. 1 and 2 may be made up of two generally similar elements formed of relatively wide thin steel strip. One of these elements may comprise the vertically separated substantially horizontally extending front members or strips 1 and 5 which may have their outer edges in substantial vertical alignment and, if desired, these front strips may be oppositely inclined throughout all or part of their length to give greater stiffness to the buffer front element. It is particularly desirable to have such oppositely inclined stiffened front strips in the outer projecting end of the buffer element beyond the supporting or clamping device such as 20 and for this reason the strips may be oppositely inclined in a vertical plane as shown in Fig. 3, this inclined stiffened arrangement continuing or increasing, if desired, throughout the outer ends of the strips 4, 7, which may be joined by an integral connector portion 3 of suitably recurved form so as to hold the front strips or members in this desired vertically separated position. In some cases the connector portion may have diagonally or angularly arranged folded or bent edges such as 29, 31 which may be arranged in substantially rectangular position with respect to each other, and this connector may extend on the rearward side of the front strips so that its longer edge may project back away from the strips considerably further than its front curved edge 30 so that it may present a generally funnel shaped connection between the adjacent parts of the front strips or members. The other front element may comprise generally similar strips 8, 13 overlapping the other front strips between their ends 9, 14 and 2, 6, which project somewhat beyond the clamping devices 20. The outer portions 10, 12 of this strip element may be similarly oppositely inclined and may be joined by a transversely extending connector portion 11 having similarly diagonally bent edges 29, 31, if desired. These buffer front strips may be formed and bent in any suitable way as by hot bending processes by which the strips are bent around suitable forms or by die forging methods, and in some cases the strips may have their front faces 26 shown in Figs. 1, 2 and 4 ground and polished and nickel plated with advan-

tage and this distinctive finish may also be extended around the diagonal folds 29, 31 so that the rear face of the connector portions 3, 11 is similarly polished and nickel plated, if desired. This gives a desirable and striking appearance to the buffer element, especially where this transverse connection is used at the ends of the buffer front, which project out to or beyond the automobile wheels, and the other faces of the strip element may be finished in baked enamel or other less striking finish to give appropriate contrast. These two cooperating buffer front elements may be adjustably connected in any suitable way so that the buffer front is of adjustable lateral width across the automobile and two such recessed clamping devices as 20 may be used for this purpose, the projecting edges 21, 22 extending around these front strips which may be clamped in position by the clamping bolt 25 and lock washer 24, the bolt being threaded into the projection or central rib 23 on the clamping device after passing through the connecting portion 19 of a supporting member of any suitable construction. One suitable illustrative form of supporting attaching member is shown in Figs. 1, 2 and 3, as comprising a laterally extending rear portion or brace bar 15 which may be clamped or secured to the frame ends 28 or other parts of the vehicle. The outwardly bent portions 16, 17 of this supporting member of spring steel strip or the like may be inturned to form the connecting portions 18, 19 which are preferably wider than the vertical separation between the front strips, to which they may be adjustably or otherwise clamped in any suitable way. It is of course understood that these buffer members and elements may be made of spring steel strip and heat treated as by being oil quenched at the proper heat and tempered so as to give them increased resilient strength and stiffness under collision conditions. The degree of inclination of the oppositely inclined front strips or members may be varied considerably and Fig. 5 shows an arrangement in which these front strips are considerably more inclined in a backward direction from their adjacent vertically aligned edges, this extent of opposite inclination giving a correspondingly greater stiffness to this part of the buffer front or other element. In some cases also these strip members may be in each case convex or concave and flat strip members may have their outer edges bent forward instead of backward, as is shown in Figs. 4 and 5, in case this form of stiffening opposite inclination of the strip is desirable for special purposes.

Such opposite inclination of the front strips not only stiffens and strengthens them, but is also useful in forming integral rearwardly bent supporting members, of which two or four may be formed on the front strip elements of this general character and extend backward preferably with inturned ends to be secured to the automobile frame. Fig. 7 shows an illustration of this type of construction in which the buffer front may comprise two similar elements adjustably connected together to form an adjustable width buffer front extending beyond the automobile wheels. One of these buffer front elements may comprise the vertically separated front strips 32, 35 connected as shown in Fig. 7 by the rearwardly extending connector portion 34, which may have the gradually bent or rounded diagonal edges 29, 31 so as to form a funnel shaped or flattened conical bend in this end of the strip element. By rearwardly bending or displacing this connector portion and the adjacent parts of the connected horizontally extending strip members as shown in Fig. 8, the strip members adjacent this connector may be held in more inclined position which is desirable in some cases. The other corresponding front element may have the horizontally separated strip members 42, 45 joined by a similar connector portion 44 and clamping devices 50 may adjustably connect the overlapping front strips adjacent the strip ends 33, 43 so as to rigidly engage and hold both the upper and lower strips in position within suitable recesses in the connector device, which may comprise the retaining washer or member 54, and the clamping bolt 55 in each case. Of course one or more additional front strips may be used to strengthen and stiffen the buffer front as by clamping them between these clamping devices 50 where additional strength and stiffness is needed. One or both of the horizontally extending strips of each of these front elements which are oppositely inclined adjacent the clamping devices to about the extent shown in Figs. 4 and 6, may be bent backward on itself to form a supporting attaching member for connection to the automobile and, if desired, the ends of these attaching strips or members may be inturned to bring them into substantially aligned overlapping position throughout the distance between the automobile frame ends, if desired, so that a multiple thickness brace bar or laterally extending rear supporting member may be formed to give strong support to the bumper and also rigidly connect the frame ends. As shown in Figs. 6, 7 and 8, the inclined front strip 35 may be bent back on itself so as to form the rearwardly extending portions 36, 37 and the other front element may have its oppositely inclined strip 45 similarly bent backward on itself in a plane perpendicular to the plane of this front strip so as to form the rearwardly

extending supporting member 46, 47. This brings the strips substantially into line with each other and their ends may be inturned at this point so as to form the overlapping laterally extending or brace bar portion 48, 39, which may overlap throughout the entire extent between the frame ends, if desired, or may have a more limited overlapping between the strip ends 40, 49 which may be clamped in this overlapping position by the Lyon type enclosing clamping device 41. This makes this part of the buffer laterally adjustable to suit different width automobile frames and gives a strong and reliable connection with the automobile through these integral rearwardly bent supporting strips or members. The buffer front strips may have any suitable shape and may in some cases, where the range of lateral adjustment is not great, be forwardly arched or curved, as shown in Fig. 8, or they may be substantially straight between the clamping devices as shown in Fig. 2.

Figs. 9 and 10 show another form of integral connection which may be used between these vertically separated buffer strips or members of buffer front or other elements. The transversely or vertically separated strip members 60, 66 may be joined by the integral recurved connector portion 67, which may be gradually bent around between the angularly arranged bent edges 62, 64. By bending this connector portion of the buffer and the adjacent parts of these strip members 61, 65 rearward out of line with the inner parts 60, 66 of the strips, the connection may be more readily formed and this rearward bend or displacement may, as shown in Fig. 10, carry the transverse end 63 of the connector portion back through nearly ninety degrees in some cases. This gives a generally conical or funnel shaped bent connector portion in which the inner front edges of the strips are considerably closer together than their rear outer edges at the bend and this also gives the adjacent portions of the transversely separated strip members a considerable degree of opposite inclination which gradually decreases so that, if desired, the relatively straight front strips or members 60, 66 may be in substantial transverse or vertical alignment with each other. Another form of recurved connector portion of such buffer front or other elements is shown in Figs. 11 and 12 as comprising a more nearly conical bent end 69 which may be bent or displaced backward to a considerable extent, such as thirty or forty degrees more or less. The inner or adjacent front edges of this recurved connector portion are considerably less separated and have a less radius of curvature than the rear edges 72 and this more or less conical bend holds the adjacent parts 68, 70

of the transversely separated strip members in considerably inclined position so that if they are to be brought into exact or even substantial transverse alignment these strips may advantageously be oppositely twisted, 70 which brings their front adjacent edges closer to each other at an inner point such as 73, the parts of the strip members 67, 71 inside of this being at a moderate opposite inclination to each other, such as shown in 75 Fig. 4, for example, or being if desired, in substantial transverse or vertical alignment with each other. This recurved conically bent connector portion shown in Figs. 11 and 12 not only has a great degree of stiffness and strength which makes it desirable for many purposes in buffer constructions, but is also of pleasing and striking appearance, especially when the forward and outer face of the strip member around the outside of the strip end is polished and nickel plated or otherwise prominently finished, as compared to the other surfaces of the strip member or element. These buffer elements 80 may be used in buffer fronts or other portions of buffers for automobiles and the like and in some cases a buffer front element having transversely or vertically separated strip members may have two generally similar recurved connector portions of the Fig. 9 or Fig. 11 type, for instance, at its 85 opposite ends so as to form a single buffer element which may be used in connection with cooperating supporting attaching devices or in connection with a substantially complete single height buffer to form a buffer front of multiple strip or increased vertical width construction.

This invention has been described in connection with a number of embodiments, forms, proportions, sizes, parts, arrangements, materials, methods of construction, connection and use, to the details of which disclosure the invention is not of course to be limited, since what is claimed as new and what is desired to be secured by Letters Patent is set forth in the appended claims:

1. The automobile buffer comprising a pair of adjustably connected front elements formed of wide thin steel strip and each having vertically displaced substantially horizontally extending front portions and an integral transversely extending connector portion at the end of the element comprising a recurring somewhat conical bend and adjacent rearwardly bent parts of said horizontally extending front portions which are oppositely inclined to each other, and integral supporting members formed by rearwardly bent portions of said oppositely inclined portions of the diagonally opposite upper and lower strips adjacent the ends of the buffer front to bring them into substantial lateral alignment and laterally extending inturned ends on said supporting 105 110 115 120 125 130

members held together in overlapping position and adapted to be secured to the automobile frame members.

2. The automobile buffer comprising adjustably connected front elements formed of steel strip and each having vertically displaced substantially horizontally extending front portions and an integral transversely extending connector portion at the end of the element comprising a recurring somewhat conical bend and adjacent rearwardly bent oppositely inclined parts of said front portions, and cooperating buffer supporting members.
- 5 10 15 20 25 30 35 40 45 50 55 60 65
- the element comprising a recurring bend and adjacent parts of said horizontally extending front portions which are oppositely inclined to each other, and integral supporting members formed by rearwardly bent portions of said oppositely inclined portions of the diagonally opposite upper and lower strips adjacent the ends of the buffer front to bring them into substantial lateral alignment and laterally extending inturned ends on said supporting members adapted to be secured to the automobile frame members.

3. The automobile buffer comprising front elements formed of steel strip and each having vertically displaced substantially horizontally extending front portions and an integral transversely extending recurved connector portion and adjacent oppositely inclined rearwardly bent parts of said front portions, and integral supporting members formed by rearwardly bent portions of said oppositely inclined portions of said front strips adjacent the opposite ends of the buffer front to bring them into substantial lateral alignment and laterally extending inturned ends on said supporting members adapted to be secured to the automobile frame members.

4. The automobile buffer comprising front elements formed of steel strip and having vertically displaced front portions and an integral transversely extending recurved connector portion and adjacent oppositely inclined parts of said front portions, and integral supporting members formed by rearwardly bent portions of said oppositely inclined portions of said front strips adjacent the opposite ends of the buffer front and laterally extending inturned ends on said supporting members adapted to be secured to the automobile frame members.

5. The automobile buffer comprising front elements formed of steel strip and having vertically displaced front portions and an integral transversely extending recurved connector portion and adjacent oppositely inclined parts of said front portions, and integral supporting members formed by rearwardly bent portions of said oppositely inclined portions of said front strips adapted to be secured to the automobile frame members.

6. The automobile buffer comprising a pair of adjustably connected front elements formed of wide thin steel strip and each

having vertically displaced substantially horizontally extending front portions and an integral transversely extending connector portion at the end of the element comprising a recurring somewhat conical bend and adjacent rearwardly bent oppositely inclined parts of said front portions, and cooperating buffer supporting members.

7. The automobile buffer comprising connected front elements formed of steel strip and each having vertically displaced substantially horizontally extending front portions and an integral connector portion at the end of the element comprising a recurring bend and adjacent rearwardly bent oppositely inclined parts of said front portions and cooperating buffer supporting members.

8. The automobile buffer comprising connected front elements formed of steel strip and each having vertically displaced front portions and an integral connector portion at the end of the element and adjacent oppositely inclined parts of said front portions.

9. The automobile buffer front formed of wide thin steel strip and having vertically displaced substantially horizontally extending front portions and an integral transversely extending connector portion at the ends of the buffer front and adjacent rearwardly bent oppositely inclined parts of said horizontally extending front portions.

10. The automobile buffer front formed of steel strip and having vertically displaced front portions and an integral connector portion at the ends of the buffer front and adjacent oppositely inclined parts of said horizontally extending front portions.

11. The automobile buffer front comprising two adjustably connected similar elements formed of wide thin steel strip and having vertically displaced horizontally extending front members having a transversely extending integral connector portion bent to hold the adjacent rearwardly bent horizontal portions of said members at oppositely inclined vertical angles with each other adjacent said transverse portion and gradually approaching vertical alignment at points further from said transverse connector portion.

12. The automobile buffer front comprising two elements formed of wide steel strip and having vertically displaced horizontally extending front members having a transversely extending integral connector portion bent to hold the adjacent horizontal portions of said members at oppositely inclined vertical angles with each other adjacent said transverse portion.

13. The automobile buffer front comprising two adjustably connected elements formed of wide thin steel strip and each having vertically displaced horizontally ex-

tending front members having their extreme upper and lower edges in substantial vertical alignment with each other and having a recurved integral connector portion bent to hold the adjacent rearwardly bent horizontal portions of said members at oppositely inclined vertical angles with each other.

14. The automobile buffer front comprising connected elements formed of relatively wide steel strip and each having vertically displaced front members having a recurved integral connector portion bent to hold the adjacent rearwardly bent horizontal portions of said members at oppositely inclined vertical angles with each other.

15. The automobile buffer front element formed of relatively wide steel strip and having vertically displaced horizontally extending front members having portions in substantial vertical alignment with each other and having a recurved integral connector portion bent to hold the adjacent rearwardly bent horizontal portions of said members at opposing vertical angles with each other while gradually approaching vertical alignment at inner points.

16. The automobile buffer front element formed of relatively wide steel strip and having vertically displaced front members having a recurved integral connector portion bent to hold the adjacent portions of said members at opposing vertical angles with each other.

17. The automobile buffer front element formed of wide thin steel strip and having vertically displaced horizontally extending front members having their extreme upper and lower edges in substantial vertical alignment with each other and having a recurved integral connector portion somewhat conically bent to hold the adjacent horizontal portions of said members at oppositely inclined vertical angles with each other.

18. The automobile buffer front element formed of wide thin steel strip and having vertically displaced front members having a recurved integral connector portion somewhat conically bent to hold the adjacent portions of said members at oppositely inclined vertical angles with each other.

19. The automobile buffer element formed of wide thin steel strip and having transversely displaced front members having their extreme upper and lower edges in substantial transverse alignment with each other and having a transversely extending integral connector portion bent to hold the adjacent rearwardly bent portions of said front members at oppositely inclined transverse angles with each other.

20. The automobile buffer element formed of wide thin steel strip and having transversely displaced members having an integral connector portion bent to hold the

adjacent portions of said members at oppositely inclined transverse angles with each other.

21. The automobile buffer front element formed of wide thin steel strip and having vertically displaced horizontally extending portions and an integral connector portion of the strip comprising a conically bent rearwardly curved displaced portion at the end of the element holding the adjacent vertically displaced portions in oppositely inclined angular position, said vertically displaced portions being oppositely twisted adjacent said connector portion to bring them into substantially vertically aligned position with respect to each other.

22. The automobile buffer front element formed of relatively wide steel strip and having vertically displaced portions and an integral connector portion of the strip comprising a conically bent rearwardly displaced portion at the end of the element holding the adjacent vertically displaced portions in oppositely inclined angular position, said vertically displaced portions being oppositely twisted adjacent said connector portion.

23. The automobile buffer element formed of wide steel strip and having vertically displaced portions and an integral connector portion of the strip comprising a somewhat conically bent rearwardly displaced portion at the end of the element holding the adjacent vertically displaced portions in oppositely inclined angular position, said vertically displaced portions being oppositely twisted adjacent said connector portion to bring them into more nearly vertically aligned position with respect to each other.

24. The automobile buffer element formed of wide steel strip and having vertically displaced portions and an integral connector portion of the strip comprising a somewhat conically bent portion at the end of the element holding the adjacent vertically displaced portions in oppositely inclined angular position, said vertically displaced portions being oppositely twisted.

25. The automobile buffer front element formed of wide thin steel strip and having vertically displaced horizontally extending front members having their extreme upper and lower edges in substantial vertical alignment with each other and having an integral substantially funnel shaped somewhat conical connector portion bent to hold the adjacent rearwardly bent horizontal portions of said members at oppositely inclined vertical angles with each other.

26. The automobile buffer front element formed of wide thin steel strip and having vertically displaced front members having an integral somewhat conical connector portion bent to hold the adjacent portions of

said members at oppositely inclined vertical angles with each other.

27. The automobile buffer element formed of wide thin steel strip having transversely displaced front portions and an integral transversely extending connector portion at the end of the element comprising a funnel-shaped somewhat conical bend and adjacent rearwardly bent parts of said front portions which are oppositely inclined to each other.

28. The automobile buffer element formed of wide thin steel strip having transversely displaced portions and an integral transversely extending connector portion at the end of the element comprising a somewhat conical bend and adjacent parts of said portions which are oppositely inclined to each other.

29. The automobile buffer front element formed of wide thin steel strip having vertically displaced front portions and an integral somewhat conical connector portion extending rearward from the plane of said front portions, said connector portion having its inner front edges vertically separated to a considerably less extent than the corresponding rear edges of said connector portion and said front portions being oppositely inclined adjacent said connector portion.

30. The automobile buffer front element formed of wide thin steel strip having vertically displaced front portions and an integral connector portion, said connector portion having its inner front edges vertically separated to a less extent than the corresponding rear edges of said connector portion and said front portions being oppositely inclined adjacent said connector portion.

31. The automobile buffer element formed of wide steel strip having horizontally extending members provided with vertically displaced portions and an integral U-shaped bent connector portion extending rearward from the plane of said horizontally extending portions of said members, said connector portion having its inner front edges vertically separated to a considerably less extent than the corresponding rear edges of said connector portion.

32. The automobile buffer element formed of wide steel strip having horizontally extending members provided with vertically displaced portions and an integral recurved connector portion extending rearward from the plane of said horizontally extending portions of said members, said connector portion having its inner front edges vertically separated to a considerably less extent than the corresponding rear edges of said connector portion.

33. The automobile buffer front element formed of wide thin steel strip having vertically displaced front portions and an integral recurved somewhat conical connector

portion extending rearward from the plane of said front portions, said connector portion having its inner front edges vertically separated to a considerably less extent than the corresponding rear edges of said connector portion.

34. The automobile buffer front element formed of relatively wide steel strip having vertically displaced front portions and an integral somewhat conical connector portion, said connector portion having its inner front edges vertically separated to a considerably less extent than the corresponding rear edges of said connector portion.

35. The automobile buffer front element formed of relatively wide thin steel strip having vertically displaced substantially horizontally extending front portions and a transversely extending connector portion at the end of the element comprising a funnel-shaped somewhat conical bend and adjacent rearwardly bent parts of said horizontally extending portions which are oppositely inclined to each other, said front portions gradually coming into vertical alignment at points further removed from said connector portion.

36. The automobile buffer front element formed of relatively wide steel strip having vertically displaced substantially horizontally extending front portions and a transversely extending connector portion at the end of the element comprising a somewhat conical bend and adjacent rearwardly bent parts of said horizontally extending portions which are oppositely inclined to each other, said front portions coming into vertical alignment at points further removed from said connector portion.

37. The buffer element formed of relatively wide steel strip having transversely displaced body portions and an integral transversely extending connector portion at the end of the element comprising a funnel-shaped bend and adjacent rearwardly bent parts of said body portions which are oppositely inclined to each other, said body portions coming into transverse alignment at points further removed from said connector portion.

38. The buffer element formed of relatively wide steel strip having transversely displaced body portions and an integral connector portion at the end of the element comprising a recurved bend and adjacent rearwardly bent parts of said body portions which are oppositely inclined to each other, said body portions coming into transverse alignment at points further removed from said connector portion, said connector portion having its inner front edges transversely separated to a considerably less extent than the corresponding rear edges of said connector portion.
